UNITED STATES PATENT OFFICE.

WILLIAM DOULIN, OF YOUNGSTOWN, OHIO.

HANGING CARRIAGE-BODIES.

Specification of Letters Patent No. 25,958, dated November 1, 1859.

To all whom it may concern.

Be it known that I, WILLIAM DOULIN, of Youngstown, in the county of Mahoning and State of Ohio, have invented certain new and useful Improvements in Hanging Carriage-Bodies; and I do hereby declare the following to be a full, clear, and exact description of the construction and operation of the same, reference being had to the accompanying drawings, making a part of this specification, in which—

Figure 1 represents a perspective view; and Fig. 2, a longitudinal section through the reaches, and springs.

Similar letters where they occur in the separate figures denote like parts in both.

When carriages drop into a depression or strike against any obstruction, the springs are liable to be thrown out of their proper positions and buckle. The recoil too, makes a heavy jar or jolt.

My purpose is to avoid these evils by a special contrivance, which I will hereafter describe.

I am aware that various means have been essayed to remedy the defects mentioned, and that among them, a spiral spring has been arranged longitudinally upon the reach, with an arm connecting the body of the carriage with it. This to a certain extent prevents the pitching of the body, but does not prevent the rebound—and this spiral spring too effects but the single purpose of counteracting the swaying of the carriage body, while my invention makes the spring available for this, as well as for the purpose of a spring to the load carried, and a preventative to the recoil or rebound.

My invention consists in combining with the springs at the ends of the carriage body, an elliptic spring on the reach, which latter has its segments hinged to the plate, and its leaves reversed—that is placed within the ellipse instead of on the outer side thereof, as will be explained.

To enable others skilled in the art to make and use my invention, I will proceed to describe the same with reference to the drawings.

A, represents the front, and B, the rear axle of a carriage, and C, D, ordinary elliptic springs placed thereon, though any other known springs may be used on or over the axles.

E, is the usual reach, connecting the front and rear axles, and F, a second reach parallel with the reach E. Between, and about midway of the length of the reaches E, F is placed an elliptic spring G, parallel with the reaches in their lengthwise direction, and secured thereto by proper plates or bearings as at a, a Fig. 1.

The spring G, is constructed as follows: Its segments b, b, b, b, are hinged to the plates a, a at the points c, c, c, c, so that they may swing freely thereon on the rebound of the spring, but act as a resisting medium when any sudden weight or jar comes upon them. The leaves d, d, of the spring G, are on the interior of the ellipse, and are rigid at the middle, and loose at their ends, but their points bearing against the segments b. These leaves, so arranged prevent the carriage body from rising suddenly or with a jar, on the rebound, as they are assisted in rising by the segments as follows: when there is a downward surge upon the spring G, the leaves d, d, at their points separate from and leave the segments b—both the leaves and segments resisting the downward force, but when it is removed the spring reacts, and the points of the leaves come against the segments and by their own elasticity counteract all sudden rebound. The spring G, thus serves three purposes, viz: it is a spring to the body in a vertical line, as ordinary springs are:—it prevents the buckling of the front and rear springs by holding them in vertical positions; and thirdly it takes the rebound or recoil off from the other springs onto itself, and eases it off gently.

The segments b, are united at the points e, in the usual manner.

Having thus fully described the nature and object of my invention what I claim therein as new and desire to secure by Letters Patent is—

In combination with any of the ordinary springs of a carriage, an elliptic spring G, on the reach of the wagon, said elliptic spring being constructed and arranged in the manner and for the purpose herein set forth and explained.

WM. DOULIN.
